TELESCOPIC SELF-SEALING CONTAINERS

George Arlington Moore, New York, N.Y.

Application April 11, 1958, Serial No. 727,928

8 Claims. (Cl. 229—34)

This invention relates to containers of paper-board or other sheet material, and more particularly to novel feature embodiments in the structure formed of the sheet material, the form of construction being made adaptable for assembly with a tubular shaped component formed of similar sheet material or of transparent plastic material and thus provide a novel and self-sealing display container for use in marketing commercial products such as articles of merchandise including food-stuffs and other commodities in general except liquids.

Conventional containers such as folding cartons have been provided with a window in a cut out section of a wall of the carton for visible display of its contents. Such cartons therefore can not have the basic protection provided for the contents thereof by being overwrapped with protective sheet material usually employed for cartons made without windows. The opposite end closures of the window cartons are folded and glued in separate stages by complicated and expensive carton set-up and closing machinery. The closures are seldom tight enough to be leak-proof. Another conventional type of container used by packers is a five sided tray folded of paper-board and overwrapped with cellophane or other transparent sheet material in order to protect and visibly display the tray contents. Such containers are of flimsy construction and requires expensive overwrap machine operation to complete the container, the wrapper being seldom taut around the tray thus resulting in the above mentioned flimsy construction.

The present invention contemplates an improvement on the above types of conventional containers and one of the prime objects herein is to provide a new and novel container construction wherein by a simple and inexpensive operation of assembling two structural components together the container is completed with end closures formed in the one simple operation.

Another object of the invention is to provide an improved container having novel structural means to produce resilient coactive effects upon the assembly of the two component parts that closes and substantially seals the container initially and after periodic dispensing of portions of its intended contents.

A further object of the invention is to provide a container of the above type with substantially impervious interior wall surfaces and structural means having self-compensating effects to maintain a constant snug-fitting relationship of the two structure forming components that constitutes the container.

A still further object of the invention is to provide an improved container having novel means for affording good protection as well as clear visible display of the particular product intended for the container.

Another object of the invention is to provide in a container made of foldable sheet material wherein a novel joint construction at the converging corner ends of the transversely disposed walls thereof is effective to promote the forming of tight end closures.

2

The above and other objects with attendant advantages are attained by this invention an embodiment of which, I have illustrated in the accompanying drawings. It is to be expressly understood, however, that the drawings are utilized for the purpose of illustration only, and are not to be taken as a definition of the limits of the invention, reference being had for this purpose to the appended claims.

In the drawings, wherein similar reference characters refer to similar parts throughout the views shown;

Fig. 1 is a partial plan view of a blank having substantially like ends and adapted to be formed into the major component part of a container of the above type;

Fig. 2 is a plan view showing a fragmentary portion of a similar blank embodied with a modification upon the ends thereof;

Fig. 3 is a perspective view of the component part as formed from the blank of Fig. 1 and shown partially engaged with another component part in assembly relationship constituting the container;

Fig. 4 is a perspective view showing the completed assembly of the component parts constituting the closed and self-sealed container;

Fig. 5 is a fragmentary sectional view of the container shown in Fig. 3 taken along line 5—5 showing the converging corner construction of the component formed of the blank shown in Fig. 1;

Fig. 6 is a fragmentary sectional view of the assembled container shown in Fig. 3 taken along line 6—6 showing the resilient co-active relationship of the component parts assembly;

Fig. 7 is a partial plan view of the container showing the converging corner construction of the component parts assembly thereof, a side wall portion of one component part being shown in cross section; and

Fig. 8 is a partial sectional view of the container structure shown in Fig. 7 taken along line 8—8 showing the end closing structural relationship of the component parts including a modification shown embodied upon the end of a wall portion of a component part thereof.

The present invention is particularly directed to a means and method of forming a novel container by having a resiliently active fitting relationship effected between two component parts when assembled together to constitute a self-closing container that is substantially self-sealing actuated by the resilient activity of its novel structure. The resiliency feature of the structure, however, being also adapted for embodiment in other types of containers made of foldable sheet material and for closure forming purposes.

To this end, an open tray-like container structure is folded of a cut and creased blank of suitable sheet material formed and secured into the desired tangible shape. The opposed side walls thereof are provided with folded marginal corner edges that form resiliently active flanges constituting at least one pair of opposed longitudinal spring active ledges and transversely thereof a pair of opposed end flanges or spring active ledges. The opposed ends of each pair of ledges are provided with novel cut edges that will form strong and tight converging corner joints to the structure of the container when it is inserted into a tubular sleeve shaped coincident to receive the tray in telescopic relationship, thereby forming a container of the present invention. Since the ledges are formed to be resiliently active and compressible, upon inserting the tray-like component into the sleeve component the walls of the tubular sleeve cause the folded marginal portions of the ledges to compress substantially together thereby effecting a snug fitting relationship of the tray to the walls of the outer disposed sleeve. The hereinbefore mentioned novel cut edges of the folded resilient

ledges have effects that strongly reinforce the end walls of the tray to withstand the thrust imposed thereupon when being inserted within the sleeve as well as being effective to stabilize the wall structure of the tray in its surface fitting relationship upon the wall surfaces of the sleeve. The sleeve component may be formed of transparent plastic material thereby providing means for visible display of the particular product intended for use of the container.

Referring more particularly to Fig. 1, the present invention is illustrated therein as including a container blank 4 which is divided into surface areas by means of a pair of longitudinal creased lines 5 and transversely thereof crease lines 6, into a base wall portion 7 and two opposed foldable side wall forming panels 8. The panel portions are each provided with a longitudinal creased line 9 and an outwardly positioned parallel creased line 10 dividing foldable marginal portions 11 and 12. The opposed end cut edge 13 of the margin 11 is disposed at right angles outwardly of the creased line 9. The adjacent end edge of the margin 12 is cut into an angular shaped notch 14. The base edge of the notch extends inwardly at right angles to the edge portion 13 of the margin 11. The base wall portion 7 is provided with opposed foldable end panels 15 disposed outwardly of the creased line 6 and inwardly of a creased line 16 disposed outwardly in spaced relation with the creased line 6. An opposed pair of cut lines 17 extend outwardly in alignment with the creased lines 5 separating the foldable extended pair of panels 18 from the end panel 15. A foldable flange portion 19 of the end panel 15 is provided with opposed cut end edges 20 and 21. The angular edge portion 20 intersects at a point with the cut lines 17 and a terminal end of the creased line 16. The edge portion 21 is disposed substantially at right angles of the end edge 22 of the flange 19. One of the end flanges 19 of the blank may be extended outwardly between its side cut edges 21 to provide any increased printing surface area as may be desired for enhancing the decorative effects of the container when assembled. The angular cut edges 14 and 20 are adapted to be engaged into abutment when assembling the container.

The sheet material of which the blank 4 is formed may be of any suitable composition that can be folded and adhered together in certain sections of its wall engaging surfaces. However, paper-board or other sheet material having at least one surface thereof applied with a plastic material such as wax, polyethylene or other film coating having required qualifications for protection of the intended product to be contained is preferable. Such plastic material utilized may have thermoplastic properties used for seam securing purposes of the blank. Wax may be applied over the surface of the thermoplastic film and thereby provide good slip and seal tension for certain areas thereof.

The structure of the blank may be modified as illustrated by the blank 4' shown in Fig. 2, wherein the flange portion extended outwardly from the end panel 15 may be modified to take the form of the flange as shown. The flange portion is divided into two foldable marginal areas 23 and 24 separated by the creased line 25 disposed outwardly of the parallel creased line 26. The foldable twin marginal flange is provided with opposed side ends cut with the edge 27 disposed at right angles between the creased lines 25 and 26. The other end 28 of the margin 24 is cut angular shape and sloped outwardly from the adjacent edge 27. A substantially square notch having cut edges 27, 30 and 31 is formed at the terminal ends of the slit cut line 17 and the transversely disposed creased line 26. The angular cut edge 28 is coincident with the angular cut edge 14 of the blank marginal portion 12, these cut edges being adapted to engage into abutments when assembling the container.

Referring now to Fig. 3 it will be seen that the blank 4 of Fig. 1 has been folded to form the component part

32 of the container. The longitudinal side walls 8 are folded about the creased lines 5 and at right angles to the central panel 7 that forms the base bottom wall closure of the component. The end panels 15 are folded upwardly and inwardly from the creased lines 6 and the panels 18 are folded inwardly from the corner ends of the side wall panels 8 in order to overlap the prior folded end forming panels 15. The end edges of the overlapping pair of panels 18 may be matched into abutment if desired and to afford maximum reinforcement to the inner folded panel wall portion 15. The interior surfaces of the formed walls 7, 8 and 15 may be plastic covered and rendered free of raw edge wicking exposure as illustrated in the cross sectional view of these walls shown in Fig. 5. The plastic coating 33 on the wall surfaces may be thermoplastic and thereby serve as an adhesive bonding agent for heat sealing the inner surfaces of the folded panels 18 upon the exterior surface of the folded end panels 15. The heat and pressure applied upon the exterior surfaces of the panels heat fuses the plastic to plastic material in the corner junctions 34 of the folded structure thereby sealing the raw cut edges 17 of the end panels 15 in a bed of the plastic material as illustrated at 34 in Fig. 5.

During or after the component 32 is formed the opposed pair of longitudinal marginal portions 11 and 12 of the side walls 8 are folded into superimposing relationship. Each margin 11 is folded inwardly and downwardly of the corresponding side wall and the marginal portion 12 is folded upwardly, outwardly and downwardly in a position to meet the outer surface of the folded marginal portion 11 thereby forming a pair of resiliently active ledges along the longitudinal corner edges of the side walls 8. It will be noted that the opposed end edges 13 of the folded margins 11 are brought into a position to register into edge to face abutment upon the corresponding interior surface of the panels 15. The angular cut end edges 14 of the folded marginal portions 12 being openly disposed upon the exterior surface of the adjacent margin 11. It will be further noted that the plastic surface of the folded marginal portions 12 is brought up-face along the top longitudinal edges of the side walls 8, the inwardly disposed corner edges 10 of the folded margins being plastic covered. The foldable flange portion 19 of the end wall panel 15 may be opposed by the flange portion 35 of the other end wall panel 15. The latter flange may be cut to provide increased surface area in order to support printed matter requirements as may be desired for the containers intended product identification.

Again referring to Fig. 3 a tubular rectangular shaped sleeve component 37 is provided to complete the structure of the container. The sleeve is preferably formed of transparent plastic material of any desired and suitable composition shaped to provide two pair of side walls 38 and 39 arranged in opposing pairs with open ends. The longitudinal length of the component 37 is coincident with the corresponding length of the component 32. The assembly of the component 32 into the component 37 constitutes the structure of the container as shown in Fig. 4. This assembly is effected by compressing the ledge margins 11 and 12 downwardly into flattened condition at one end thereof and the end edge 13 of each lower margin 11 forming an abutment upon the corresponding inner face of the adjacent end wall 15. The end wall flange 35 is folded inwardly and downwardly so that the inner surface portions that are adjacent the angular cut edges 20 thereof lie upon a corresponding surface portion of the lower folded ledge margin 11. In this condition at one end of the component 32 it is entered into an open end of the sleeve component 37 thereby further compressing the entered portion of the ledges and flange. The folded ledges have a constant tendency to spring upwardly but are resisted by the coincident surface portions of the encasing wall 39 of the

component 37. The sloped edges 14 of the compressed ledges and sloped edges 20 of the flange 35 are brought into mitred edge abutting joints at the converging corner ends of the inserted component 32. These abutted edges are formed to lie upon the upper surface portion of the lower margin 11 of the ledges, the mitred joint sloping inwardly and away from the abutted end edge 13 of the lower margin. The inwardly extended straight edges 21' of the flatly compressed flange 35 are abutted upon the corresponding corner edges 10 of the compressed ledges thereby being effective to form a truss between the pair of ledges adjacent the entered end portion of the assembly. This form of structure prevents the side walls 8 from having a tendency to spring inwardly away from the side walls 38 of the outer component part 37. The abutted end edges 13 of the lower margins of the ledges upon upper corresponding inner surfaces of the end wall panels 15 also form longitudinally disposed trusses between the end walls which strongly resists the thrust imposed upon an end wall that is necessary to further insert the component 32 into its related component 37. The resilient activity of the opposed pair of ledges cause their respective folded margin 12 to press upwardly and flatly upon the corresponding inner surface portions of the opposing wall 39 of the sleeve component 37 as shown in the cross sectional view of Fig. 6. The plastic coating 33 upon the margin 12 is conducive of good slip and cushion-like surface bearing contact upon the opposing wall 39.

The tray component may be charged with its intended contents either before or after it is entered into the sleeve component by imposing an inward thrust upon an end thereof in any suitable manner to push it into the sleeve. As it slides therein the folded margins constituting the resilient ledges are compressed into self-superimposing relationship thereby snugly fitting the exterior surfaces of the tray walls in general into contact with the interior corresponding wall surfaces of the sleeve. During the tray movement its end wall flange 19 is folded inwardly and downwardly upon the exposed surface portions of the inwardly folded ledge margins 11 and the flange edge 22 is guided to enter beneath the end edge 40 of the sleeve wall 39. The inwardly sloping edges 20 of the folded flange 19 meet in abutments with the sloped edges 14 of the ledge margins 12 thereby forming an abutted mitre joint inwardly of the adjacent corner ends at the top of the vertical side wall 8 and end wall 18. The insertion is completed when the end walls of the tray are substantially flush with the end edges of the sleeve as shown by the completed container 42 of Fig. 4. It will be noted that the exterior surfaces of the compressed end flanges 19 and 35 of the tray component are established coplanar with the exterior surfaces of its longitudinal margins 12 of the compressed ledges as illustrated in Fig. 7. These surface engagements established in general between the component parts assembly are further clearly illustrated in Figs. 6 and 8, and while such engagements are established to be effectively sliding in relationships, nevertheless, also constitutes substantially seam forming relationships in general of the container structure. This relationship is augmented by the opposed side edges 21 and 21' of the end flanges 19 and 35 respectively, having been provided with a pair of straight edge portions 21 and 21' that are abutted with corresponding portions of the longitudinal corner edges 10 of the compressed ledges thereby constituting a pair of trusses spread between the pair of transversely disposed ledges thus serving to prevent the opposing pair of longitudinal side walls 8 of the inserted component 32 from having any tendency to lose their snugly fitted surface to surface relationship established upon the inner surfaces of the retaining side walls 38 of the component 37. The transparent wall 39 framed by the pair of ledges and the transversely disposed flanges provides a unique window panel for clear visible display of the product intended for the container. The container

when initially closed may be provided with a tamper-proof stamp or label 43 adhesively attached over an end thereof as shown in Fig. 4 and thereby augment the seal of the container.

5 The tray component may be cushioned lined inside with various types of protective material for protection of fragile articles that may be intended for the container. For certain other types of products to be contained that need moisture or grease barrier protection, the interior 10 of the tray component is preferably faced with plastic film material having desired qualities including thermoplastic properties such as the lining of plastic hereinbefore described. In this respect the sealing efficiency of the tray in the sleeve can be increased by applying a coating of 15 plastic film material upon the exterior surface of the end flanges 19 and 35. Hence, the surface engagements of the flanges with the sleeve wall 39 will be also plastic to plastic same as the relationship established for the ledge margins 12 and the plastic wall 39. By this arrangement 20 the engaging wall 39 upon the end flanges with mitred joints established with the ends of the marginal portions 12 of the ledges will constitute a plastic surface sealed closure of the container by the simple operation of inserting the tray home in the sleeve, the seal being effected 25 by the resiliency of the ledges that are maintained in coplanar surface bearing relationship with the interior surface of the wall closure 39. If desired, the plastic sleeve 30 37 may be of molded form and the closure constituted wall portion 39 thereof provided with an end edge having 35 a slight bead 45 formed on the inner surface portion adjacent one end edge 40 as shown in Fig. 8. The bead will function to provide a stop point for the inserted tray. By applying wax over the surfaces of the tray, surface 40 engagements with the walls of the sleeve component are lubricated thereby providing means for easy slip upon the engaging surfaces when moving the tray in and outwardly of the sleeve including increased efficiency to be derived in effecting the self-sealing ability of the container. A substantially air-tight seal of the tray within the sleeve 45 can be obtained by warm-heating the walls of the sleeve just enough to soften the wax film and upon cooling the walls, the wax will harden thereby constituting the air-tight sealing means. The surface tension adhesion will yield, however, by pressure applied inwardly upon an end wall of the tray component to open the container.

50 Should it be desired to form a resilient ledge on the end wall 15 of the tray in lieu of one or both of the described flanges 19 and 35 respectively, then, the marginal portions 23 and 24 of the end wall 15' illustrated in Fig. 2 are folded on the score lines 25 and 26 precisely as hereinbefore described for folding the marginal portions 11 and 12 that forms the pair of longitudinal ledges of side wall 8. The opposite end edges 27 of the margin 23 will be adapted to form an abutment with a portion of the corner edges 10 of the longitudinal ledges. The mitred ends 28 of the marginal portion 24 will be formed into mitred joints being adapted to abut with the mitred end edges 14 of the transverse ledges. These mitred joints will lie upon the lower margin 11 of the ledges in 55 the same manner provided for the folded flanges 19 and 35 in forming mitred joints. By thus forming a resilient ledge on at least one end wall of the tray component that in cross section is similar to the view shown in Fig. 6 except for the wall portion 38, the result obtained would 60 be to augment the efficiency of the surface tension seal of the container.

65 Within the scope of the present invention, the defined closure forming ledge structure of adjacent side walls of the container is contemplated to be applicable for embodiment in closure constructions for other types of containers formed of folded sheet material such as folding cartons and shipping cases. The ledge structure as defined herein is suitably adapted to engage with the surface of a folded end segment constituting a closure form-

ing wall panel portion of the carton or shipping case and in seam forming relationship.

While simple modifications of the invention have been illustrated and described, it will be understood, by those skilled in the art, that various changes may be made therein without departing from the general spirit of the invention. Reference will therefore be had to the appended claims for a definition of the limits of the invention.

What is claimed is:

1. A telescopic self-sealing container formed of two component structural parts assembled together comprising the first part constructed of a folded blank that provides a tray-like structure having a flat bottom wall with integrally related side walls thereof arranged in one opposing pair and joined with a pair of adjacent end walls, the top of each side wall being provided with a longitudinal ledge formed of two-ply folded marginal portions defined by first and second folded margins disposed inwardly at substantially right angles along its dependent side wall, the first and lower folded margin having its opposite end edges disposed in edge to surface abutments upon the interior surfaces of said end walls adjacent the top thereof, the second folded margin being superposed over said first folded margin in resiliently free relationship and having its opposite end edges mitred and sloped inwardly from the corner end of side and end walls thereby forming a pair of opposed longitudinal resiliently active ledges on said one pair of side walls and having a constant tendency to spring upwardly and thereby resist being flattened, said end walls each being provided with a top flange portion having opposite side edge portions mitred sloping inwardly and further extended with a straight side edge portion, said flange being folded inwardly and downwardly of its dependent end wall and said mitre edge portions each being aligned with a mitred end edge of said resiliently free marginal portion of said pair of ledges, said extended straight edge portions of the flange being aligned with the longitudinal corner fold edge of said two-ply margins of the ledges, said first part defined being inserted into the second component part consisting of a tubular body with open opposite ends and flat side walls that enclose the bottom and one pair of side walls including the open top of the inserted first part, the co-acting effects of said insertion flattening said pair of ledges compressibly against their inherent resiliency whereby the total engaged surfaces of said assembly are intimately exerted into surface upon surface sealing relationship of the two component structural parts constituting the container, said end wall flanges and mitred edges being flattened into coplanar surface relationship with the outer-ply margin of the pair of flattened ledges and forming mitred joints enclosed by one wall of the second component, said end walls of the first component constituting opposite end closures of the self-sealed container.

2. A telescopic container according to claim 1 wherein said first component part is provided with interior surfaces of protective plastic film material constituting a substantially impervious surface interior, said second component part being composed of transparent plastic material and whereby the surface portions of said outer-ply margins of the ledges are plastic, pressed in plastic to plastic non-adhered surface sealing relationship with the enclosing wall of the second component effected by the resilient activity of said pair of ledges of the first component.

3. A telescopic container according to claim 1 wherein said first folded marginal portion of the ledges being constituted to form a pair of opposed longitudinal trusses extended between the end walls of the first component effected by said edge to surface engaged abutments thereof, said trusses being effective to strongly resist the exerted pressure upon one of said end walls when inserting the first component into the second component.

4. A telescopic container according to claim 1 wherein the opposite straight side edge portions of each said folded end wall flange is abutted upon the corresponding part of the longitudinal corner fold edge of said flattened ledges thereby forming a truss extended transversely between the pair of ledges adjacent the opposite ends thereof and constituted by said end wall flanges, whereby the exterior surfaces of the one pair of longitudinal side walls of the first component is maintained in pressure bearing relationship upon the opposing interior surfaces of the side walls of said second component.

5. A telescopic container according to claim 1 wherein said mitred pair of edges of each end wall flange portion slopes inwardly and being disposed upon the exterior surface of each of said first folded ledge margin and adjacent the end wall abutted end edge thereof.

6. A telescopic self-sealing container comprising a tray-like component part thereof having a bottom, side and end walls, the side walls being provided with folded and resiliently active ledge margins extending the full length on the top of said walls and each ledge consisting of a lower marginal portion thereof folded inwardly and downwardly of its dependent wall and having its opposite end edges abutted upon the respective opposite inner corresponding surface portions of the opposing end walls, an upper marginal portion of the ledge being folded upwardly, outwardly and downwardly in superposed surface relationship with the first folded portion and which is resiliently free to spring upwardly, the opposite ends of the second folded margin being provided with mitred edges sloped inwardly from the corner end of said side and end walls and over the exterior surface of said first folded margin, a flange portion projected from the top edge of each end wall being provided with a pair of opposed mitre edges sloped inwardly from the top of the corner ends of side and end walls complementary with said mitre ends of the ledges, said flange portion being folded inwardly and downwardly in the plane of said second folded marginal portion of the ledges and the complemented mitre edges forming mitred joints disposed upon the exterior surface portions of said first folded margins adjacent its abutted ends upon the end walls, said tray being inserted into a tubular sleeve component part of the container whereby, said ledges being resiliently active, press upwardly upon the top wall of said sleeve augmented by said end flanges thereby causing the bottom and side wall surfaces of the tray to snugly engage upon the interior surfaces of the sleeve in surface to surface sealing relationship constituted by the assembly closing together of said component parts to constitute said self-sealing container.

7. A self-sealing container comprising a tray having four flat side walls arranged in opposing pairs and being folded at right angles from corner edges of a bottom wall portion, each of two of said side walls opposed being provided with a double folded narrow ledge superposed in marginal relationship articulated inwardly along the top corner edge of the dependent side wall, the lower margin being provided with straight cut opposite ends and the upper marginal portion with mitred cut opposite ends that are sloped inwardly from the top corner ends of adjacent side walls, each of the other two opposed side walls being provided with an inwardly folded flange articulated along the top end thereof and having a mitred edge portion on its opposite side ends complementary with said mitred ends of the upper margin of the ledges, the upper face of said ledges and flanges being film coated to provide a lubricant and non-adhered sealing agent between flat surfaces and when sliding said tray inwardly and outwardly of a tubular sleeve having four flat side walls to encase the tray whereby, upon entering and sliding said tray home within said sleeve, the ledges and flanges are compressibly flattened into coplanar surface relationship upon the inner surface of the enclosing wall portion of the sleeve thereby forming mitre joints ad-

adjacent the corner ends of the adjacent side walls of the tray and said joints being sealed between said lower marginal portion of the flattened ledges and the enclosing wall portion of said sleeve effected by the co-acting resiliency of the flatly compressed ledges of the constituted self-sealing container.

8. A flat blank of foldable material adapted to be formed into a tray-like container having four side walls arranged in opposing pairs and an integral bottom wall, said blank comprising a sheet of said material provided with scored lines defining rectangular wall panels and cut to define a pair of foldable longitudinal side wall panels and another pair of foldable transverse end wall forming panels, the latter panels consisting of a foldable full panel extended from the defining end of said bottom forming wall panel, and two opposed foldable panel portions extended from each defining end of said pair of said wall forming panels, said full panel being separated from the other pair of panel portions by slit lines defining said edges of the full panel, said full panel being provided with a foldable flange defined with a score line extending transversely between said slit lines, the opposed side cut ends of the flange being shaped to provide a mitred edge portion sloped outwardly from the terminal end of said score line and the mitre ending in a straight edge portion in parallel with the adjacent slit line, the first mentioned pair of longitudinal panels each being pro-

vided with a pair of parallel score lines defining the longitudinal end of the panel portion and twin foldable marginal portions separated centrally by one of said score lines to define an inner and outer margin, said inner marginal portion being provided with opposite ends cut straight and having a transversely disposed edge portion in line extending from an end of said central score line, said outer marginal portion being provided with opposite ends cut mitred to form a notch joining the outer transverse cut edge portion of said inner margin, said mitred cut edges of the flange and outer margin being adapted to complement each other in forming mitred joint connections when folding the blank to form said tray-like container.
